Attorney.

UNITED STATES PATENT OFFICE.

DONALD McDONALD, OF LOUISVILLE, KENTUCKY.

COKE-QUENCHING APPARATUS.

No. 832,693.

Specification of Letters Patent.

Patented Oct. 9, 1906.

Application filed March 9, 1906. Serial No. 305,165.

To all whom it may concern:

Be it known that I, DONALD McDONALD, a citizen of the United States, residing in Louisville, in the county of Jefferson and State of Kentucky, have invented certain new and useful Improvements in Coke-Quenching Apparatus, of which the following is a specification.

This invention relates to coke-quenching apparatus; and it has for an object to improve that type of quenching apparatus in which the coke is placed in a quenching-bin and then delivered to a car or other conveying apparatus.

15 A further object is to provide a means for collecting the hot water which discharges from the quenching-bin.

Other and further objects will appear in the following description and will be more 20 particularly pointed out in the appended claims.

In the drawings, Figure 1 is a sectional view through a portion of a retort-house employing my invention, and Fig. 2 is a sectional view at right angles to the view shown in Fig. 1.

Referring more particularly to the drawings, 1 indicates the retorts, arranged in vertical rows, as usual. Below each vertical row 30 or bench is arranged a bin 2, the top of which is on a level with the top of the main floor 3 of the gas-works and is closed by a pair of doors 4 and 5, hinged at 6 and 7 to opposite sides of the bins. The door 4, which is nearer the vertical row of retorts or bench, swings 35 upwardly and rests upon a support 8, which holds it at the proper angle to form a slide or chute for directing the coke from the retorts to the bin. The door 5 swinging in the reverse direction acts as a guard to prevent the coke passing onto the main floor 3. When 40 both doors 4 and 5 are closed, there is formed a platform upon which the stokers may walk to fill the retorts, the platform at the same time serving to prevent coal falling in the bin. The bins 2 depend into the cellar 13, and each has its bottom formed by a pair of 45 alined walls 9 and 10, one of which, 10, is hinged at its upper edge at 11 and is secured at its lower end to the lower edge of the other wall by a fastening 12. The other wall 9 acts to direct the coke into a car 14, running on tracks within the cellar below all the bins.

Extending across the top of the bin, about 55 the middle thereof, is a spray-pipe 15, which connects with a pipe 16, common to all the

bins, the latter pipe 16 receiving its supply from a pipe 17. The spray-pipe 15 in this position produces a complete spraying of the coke and does not interfere with the passage 60 of the coke to and from the bin. The lower end of the door 10 does not extend completely to the end of the wall 9, so that a water-discharge 18 is provided. Each discharge 65 delivers onto an inclined plate 19, located above the floor of the cellar of the retort-house and beneath each bin 2 and in turn discharging into a trough 20, common to all of the bins. These inclined plates are hinged at 21 at their lower ends to the trough, 70 so as to be movable to permit the discharge of the coke from the bin, and are supported in a raised position at their upper ends by hooks 22, which engage projection 23 thereon and are suspended from the I-beams 24, sus- 75 taining the floor 3.

The operation of the invention is as follows: During the filling of the retorts in the usual manner the doors 5 and 6 are closed. After the gas is made these doors are opened, 80 the bottom door 10 being closed, and the coke is removed from the retorts by any suitable apparatus. In passing therefrom it drops upon door 5 and slides into the bin. While the hot coke is being drawn it is 85 quenched by water from the spray-pipe 15, and the steam resulting from the quenching is carried away by the natural draft caused by the heat of the mouthpieces and stand-pipes. When the drawing of the coke is fin- 90 ished, the doors 4 and 5 are closed, and the spraying is continued long enough to completely quench the coke, but not to cool it. The doors remain closed and the coke re- 95 mains in the bins for several hours, until it is cooled and dried, the cooling and drying in the presence of steam greatly improving its appearance. The water after quenching the coke discharges through outlet 18 onto the inclined plate 19, from which it passes into 100 trough 20, which leads to any suitable outlet. In this manner all the hot water is conducted outside of the retort-house, and the hot water does not drop to the floor and make steam, which is a positive nuisance. The water as 105 it flows from the trough contains some breeze and dirt, which being heavy settles out of it immediately, leaving the water clean and clear and ready to be pumped up and used over again if the cost of the water justifies it, 110 in this way effecting a great economy of water. During the draining of the coke the

retorts are refilled, and after the draining the inclined plates are dropped downwardly, as shown in dotted lines, Fig. 1, and the doors 10 opened, permitting the coke to be discharged into the car.

Having thus described my invention, what I claim, and desire to secure by Letters Patent, is—

1. The combination with the retorts, of a bin located to receive material from the retorts, a hinged closure adapted to swing toward the retorts to form a chute, and a hinged closure adapted to swing away from the retorts to form a guard.
2. The combination with the retorts, the cellar below the retorts, and the main floor, of a bin suspended from the main floor to receive the coke from the retorts, and means arranged above the floor of the cellar of the retort - house to catch the hot water discharged from the bin.
3. The combination with the retorts, of a bin, located to receive the coke from the re-

torts, and means arranged above the floor of the cellar of the retort-house to catch the hot water discharged from the bin; said means being movable to permit the discharge of the coke from the bin.

4. The combination with the retorts, of a bin located to receive the coke from the retorts, and a movable plate receiving the hot water discharged from the bin.

5. The combination with the retorts, of a bin located to receive the coke from the retorts, and a hinged plate receiving the hot water discharged from the bin.

6. The combination with the retorts, of a bin located to receive the coke from the retorts, a trough, a plate hinged below the bin to the trough, and means for holding the upper end of the plate in a raised position.

DONALD McDONALD.
